UNITED STATES PATENT OFFICE.

ROBERT DAWES, OF PHILADELPHIA, PENNSYLVANIA.

SPINNING AND TWISTING MACHINE.

SPECIFICATION forming part of Letters Patent No. 554,217, dated February 4, 1896.

Application filed May 27, 1895. Serial No. 550,813. (No model.)

To all whom it may concern:

Be it known that I, ROBERT DAWES, a citizen of the United States, residing in Philadelphia, Pennsylvania, have invented certain 5 Improvements in Spinning and Twisting Machines, of which the following is a specification.

My invention consists of certain improvements in the spinning and twisting machine 10 for which I obtained Letters Patent numbered 481,787, dated August 30, 1892, the objects of my present improvements being to automatically regulate the tension or drag upon the winding-spool, to automatically stop 15 the machine when the spool has been fully wound, and to prevent the starting of the machine until the tension-regulating devices are in proper position. These objects I attain in the manner hereinafter set forth, reference being had to the accompanying drawings, in which—

Figure 1 is a longitudinal section of sufficient of the machine to illustrate my present 25 improvements. Fig. 2 is an end view looking in the direction of the arrow, Fig. 1. Fig. 3 is a plan view of the tension-regulating mechanism with the frame and some of the other parts shown in section on the line 3 3, and Fig. 4 is a diagram illustrating a modification of part of the invention.

So far as regards the spinning and twisting devices of the machine and the devices for laying the twisted rope properly upon the spool they are substantially the same as those of the 35 machine previously patented, and hence will require no special description further than to say that the flier A is driven by a belt from a pulley A' on the main shaft B, and that the flanged pulley a is carried by a sleeve which 40 is connected to the spool and serves to retard the rotation of the same under the pull of the rope which is being wound thereon, said pulley receiving a belt a', which passes round a flanged pulley a' on the shaft B, this pulley 45 being so proportioned in respect to the pulley A' that the spool is driven at a slightly lower speed than but in the same direction as the flier, the pulley a slipping under the belt a' at a rate dependent upon the difference in 50 the speed of the flier and spool. Hence said belt a' serves as a frictional retarder for the spool. This frictional retardation of the

spool should be slightest when the winding first begins and gradually increases in force as the spool becomes filled, and one of the 55 objects of my invention is to effect such automatic graduation of the friction, an object which I attain in the following manner:

The machine has the usual longitudinally-reciprocating frame D with guide for the rope, 60 so as to lay the latter uniformly from end to end of the spool, and this frame has an arm D', which engages with adjustable collars d' on a sliding bar d mounted in suitable guides in the frame and having ratchet-teeth d² 65 adapted to engage with the teeth of a ratchet-wheel f on a vertical shaft f', so that as the bar d is moved in one direction the wheel f will be turned forward thereby, a suitable pawl f² preventing the ratchet-wheel from 70 moving backward as the bar d is moved in the opposite direction, the teeth d² of the bar then slipping over the teeth of the ratchet-wheel.

By adjusting either or both of the collars 75 d' on the bar d the extent of movement of the bar on each reciprocation of the frame D can be accurately regulated to accord with the size or character of the rope which is being wound, and to cause a quick, slow, or medium 80 action of the tension devices only one of the collars need be adjustable.

The shaft f' is adapted to suitable bearings in a hanger f³ and is provided with a worm f⁴, which meshes with a worm-wheel g on a 85 shaft g', to which is also secured a cam-disk g² adapted to act upon a lug i' on an arm i, which is pivoted to a stud i² upon the frame of the machine and has at the upper end a flanged pulley i³, which bears upon the belt 90 a' in its passage between the pulleys a a'. The spindle k of the pulley i³ is adapted to a segmental slot k' in the upper end of the arm i and can be secured in any position of adjustment in said slot by means of its nut k², 95 so that the pulley i³ can primarily be caused to bear with any desired degree of force against the belt a'.

When the machine commences to wind the rope upon the spool, the lug i' of the arm i 100 occupies a position on the lowest portion of the cam g², as shown in Fig. 2, but as the operation of the machine continues said cam is turned in the direction of the arrow, Fig. 2,

so as to gradually move the arm i inward and cause the pulley v^3 to bear with constantly-increasing force against the belt i' and thus constantly and gradually increase the friction exerted upon the pulley a , thereby gradually augmenting the drag upon or retardation of the spool to accord with the gradually-increasing weight of the same due to the increased diameter of its load of rope, the lug 5 i' finally reaching the highest portion of the cam g^2 by the time the spool is fully wound. The shaft g' also carries an arm m , as shown in Fig. 1, this arm being adapted to act upon the under side of a shipper-rod m' which 10 controls the driving-belt of the machine. Normally this shipper-rod is retained in position to direct the belt to the fast pulley n upon the driving-shaft by reason of the engagement of a shoulder m^2 of the rod with a guide-bracket m^3 on the frame. By the time the 15 spool is fully wound, however, the arm m has acted upon the shipper-rod so as to lift the same sufficiently to free its shoulder from engagement with said guide-bracket, thereby 20 permitting movement of the shipper-rod under the action of a spring m^4 , so as to direct the driving-belt onto the loose pulley n' and thus stop the operation of the machine, the pivot-pin p of the shipper-rod being adapted 25 to a slot p' in the frame, so as to permit of this longitudinal movement of the rod. After the filled spool has been removed from the machine and a fresh spool inserted the shaft f' is turned by means of a hand-wheel s , so 30 as to continue the forward movement of the cam g^2 until the lug i' of the arm i again rests upon the low portion of the cam, the tension of the belt a' tending to move the arm i constantly outward, so as to press said lug i' toward the face of the cam. The same movement of the cam g^2 also carries the arm m so 35 far forward as to permit the lowering of the shipper-rod m' sufficiently to cause it to again engage with the guide-bracket m^3 when said 40 shipper-rod has been retracted so as to again direct the driving-belt onto the fast pulley i , this operation being effected by hand, but being impossible until the movement of the cam g^2 by hand in the manner before set forth has 45 first been effected. Hence it is impossible to start the machine until the tension devices are in normal starting position.

Where the character of the rope produced by the machine is uniform, and the action of the belt-tightener v^3 can consequently also be uniform, the cam g^2 can, if desired, be driven in a manner different from that illustrated in Figs. 1, 2 and 3. For instance, the shaft B may have a worm v meshing with a worm-wheel v' on a shaft v^2 , which has a worm v^3 for driving the wheel g on the cam-shaft g' .

Having thus described my invention, I claim and desire to secure by Letters Patent—

65 1. The combination of the frictional retarder for the winding-spool of a spinning or twisting machine, one of the elements of which

frictional retarder is a belt passing round a pair of pulleys, an arm carrying a pulley acting upon said belt so as to increase the tension of the same when moved in one direction and decrease the tension when moved in the opposite direction, a cam for acting upon said arm, and means for operating said cam, substantially as specified. 75

2. The combination of the frictional retarder for the winding-spool of a spinning or twisting machine, a longitudinally-reciprocating frame, a tension device acting upon said frictional retarder, a cam for operating said tension device, and mechanism whereby the reciprocating movement of the frame is caused to impart rotating motion to said cam, substantially as specified. 80

3. The combination of the frictional retarder for the winding-spool of a spinning or twisting machine, a longitudinally-reciprocating frame, a tension device acting upon said frictional retarder, a cam for operating said tension device, and mechanism whereby the reciprocating movement of the frame is caused to impart rotating motion to said cam, one of the elements of said mechanism being a bar with adjustable collar to be struck by an attachment of the reciprocating frame, so as to vary the extent of movement imparted to the bar by the frame, substantially as specified. 85 90 95

4. The combination of the frictional retarder for the winding-spool of a spinning or twisting machine, a longitudinally-reciprocating frame, a tension device acting upon said frictional retarder, a cam for operating said tension device, a cam-shaft having a worm-wheel, a worm engaging with said worm-wheel, and having a shaft with ratchet-wheel, and a ratchet-bar engaging with said ratchet-wheel and operated by the reciprocating frame, substantially as specified. 100 105

5. The combination of the frictional retarder for the winding-spool of a spinning or twisting machine, a tension device acting upon said frictional retarder, a belt-shifter, and means for actuating said tension device and belt-shifter, the latter operating before the tension-operating device has completed its movement, substantially as specified. 110 115

6. The combination of the frictional retarder for the winding-spool of a spinning or twisting machine, a longitudinally-reciprocating frame, a tension device acting on said frictional retarder, a belt-shipper, a shaft having a cam for operating the tension device, and an arm for tripping said belt-shipper, and means whereby the reciprocating frame is caused to impart rotating motion to said shaft, substantially as specified. 120 125

7. The combination of the frictional retarder for the winding-spool of a spinning or twisting machine, a tension device acting upon said frictional retarder, a cam for operating said tension device, means for automatically actuating said cam, and provision whereby said cam can also be actuated by hand 130

independently of the automatic actuating devices therefor, substantially as specified.

8. The combination of the frictional retarder for the winding-spool, a tension device 5 acting upon said frictional retarder, a shaft having a cam for operating said tension device, means for automatically rotating said shaft, a belt-shifter, a retainer therefor, an arm on the cam-shaft adapted to trip said 10 belt-shifter before the tension device has completed its movement, and provision for rotat-

ing the shaft by hand to complete the movement and advance the tripper-arm so as to permit of the readjustment and retention of the belt-shifter, substantially as specified. 15

In testimony whereof I have signed my name to this specification in the presence of two subscribing witnesses.

ROBERT DAWES.
